(57) **CLAIM**

The ornamental design for an electric massaging chair, as shown and described.

DESCRIPTION

FIG. 1 is a perspective view of the electric massaging chair; FIG. 2 is a front view thereof;

FIG. 3 is a right side view thereof;

FIG. 4 is a top plan view thereof;

FIG. 5 is a bottom plan view thereof;

FIG. 6 is a left side view thereof; and,

FIG. 7 is a sectional view at cross-section 7-7 of FIG. 4 omitting interior mechanism.

The portions of the article in broken lines are shown for illustrative purposes only and form no part of the claimed design.

A rear view of the electric massaging chair is a mirror image of the front view, and therefore omitted.
